John S. Gram of Hanover, State of New Hampshire

Letters Patent.

The schedule referred to in these Letters Patent and making part of the same containing a description in the words of the said John S. Gram himself of his improvement called "Gram's self pressing hanging hair Chase press." To all to whom these presents shall come.

Be it known that I John Shepard Gram, of Hanover in the County of Grafton, and State of New Hampshire, have invented a new and useful improvement for pressing Oceans and other substances, which I call Gram's self pressing hanging hair Chase Press; and that the following is a full and exact description of the construction and operation of said Improvement or machine as invented and improved by me, reference being had to the drawing annexed which is to be considered a part of said description and to the model deposited in the Patent Office.

The machine or improvement as used and applied to the pressing of hair is constructed as follows: a frame of sufficient timber, consisting of two posts six feet high or more or less fixed in timbers at the bottom so as to stand firm as will be seen in the drawing annexed marked A, connected by a piece of timber at top and bottom about three and a half feet long, said timber marked B, this is called the outer frame - a square frame of sufficient timber the side and top timbers of which are marked C, in the drawing, is to be made just wide enough to slide up and down, between the post A, in a groove fitted for the purpose in the said post, this is called the inner frame.

On the bottom piece of the inner frame, is placed a board, or under fol- lower, marked D, on which the Oceans is placed. The top piece of said inner frame is mortised and lengthwise split through, from top to under side almost the whole length of it, E, is the Chase to be pressed resting on the under board as follows: F, is a block to be placed on top of the Chase, G is a beam of wood laying horizontally just long enough to reach up and down with the inner frame, and kept in place by two pins

one passing through each end, which pins are fixed in the upper timber of the inner frame. This beam b , lies on the block a , the lower ends of A , are two hanging elbow levers attached to and passing through the top piece of the inner frame, secured by two pins c to M , top piece, said pins passing through the top piece and the levers near their lower end so as that the levers can play and forming the fulcrum of the levers, the lower end of the levers resting on the beam b , the long or elbow ends of the levers pass through long mortises, marked b , cut in the outside posts a , at the upper end of said levers at a joint marked c , the pins that make the elbow pass through the said mortises, marked b , in the posts a , to the top piece of the outer frame, and are secured to it at the dots d , where said dots are attached to the levers at the joint. There are holes or staple placed, so that the slot above may be fastened at different distances from the end of the levers as may be required. These elbows are to be of iron, brass or other rods of wood or of cords as may be preferred by the person using. In the center of the top piece of the outer frame is a mortise quite through from top to bottom, and through the top piece from front to back is placed a windlass marked b , and from b is well off a leather strap c , etc. to the upper beam of the inner frame by means of which the whole inner frame and its contents can be raised up at pleasure. The beam b is attached to the lower end of the levers A , by small leather straps to prevent the beam from falling when the cheese and block are taken from under it. By turning the windlass b , the whole inner frame is raised up - the cheese may be laid in its place for passing with the block on it, the cheese resting on the block and the lower ends of the levers resting on the beam. The inner frame is then suffered to slide down and the cheese is passed by its own weight and that of the apparatus without the addition of any other power. The windlass is then turned - The inner frame is raised, and the cheese can easily be recovered. It is needless to say the proportions of the different parts of said machine may be varied at pleasure. - Hanover November 28th 1805.
